SAFETY RESTRAINT VEST

Richard S. Chapman, 1403 Arthur Drive,
Provo, Utah 84601

Filed June 15, 1971, Ser. No. 153,481

Term of patent 14 years

Int. Cl. D2—02

U.S. Cl. D2—190

FIG. 1

FIG. 4

FIG. 2

FIG. 3

FIG. 1 is a front perspective view of a safety restraint vest showing my new design, the dash lines representing stitching;

FIG. 2 is a rear perspective view thereof, the tether portion being broken away to indicate indeterminate length;

FIG. 3 is an enlarged fragmentary front view showing the closure in a partially open position; and

FIG. 4 is an enlarged fragmentary rear view.

I claim:

The ornamental design for a safety restraint vest, as shown and described.
